[57] CLAIM

The ornamental design for an escutcheon, as shown.

DESCRIPTION

FIG. 1 is a top perspective view of an escutcheon, the broken lines shown are for illustrative purposes only and form no part of the claimed design;

FIG. 2 is a top plan view thereof;

FIG. 3 is a side elevational view, all other sides being a mirror image thereof;

FIG. 4 is a bottom plan view thereof; and,

FIG. 5 is a cross-sectional view, taken along line 5—5 of FIG. 2.
